P. G. WESTERBERG.
ELEVATOR WELL DOOR OPERATOR AND LOCK.
APPLICATION FILED APR. 18, 1914.

1,104,591.

Patented July 21, 1914.

UNITED STATES PATENT OFFICE.

PETER G. WESTERBERG, OF NEW YORK, N. Y.

ELEVATOR-WELL-DOOR OPERATOR AND LOCK.

1,104,591.

Specification of Letters Patent. Patented July 21, 1914.

Application filed April 18, 1914. Serial No. 832,778.

To all whom it may concern:

Be it known that I, PETER G. WESTERBERG, a citizen of the United States, and a resident of the city of New York, borough of Manhattan, in the county and State of New York, have invented a new and Improved Elevator-Well-Door Operator and Lock, of which the following is a full, clear, and exact description.

10 The present invention relates to an improved device for holding the gate or door of an elevator well or the like positively locked when closed so as to prevent opening thereof except by the operator of the 15 elevator and also to permit opening and closing of the gate conveniently by the operator.

With the above and other objects in view, the invention resides in the peculiar combination and arrangement of parts to be herein-after more fully described, illustrated and claimed, it being also an object to provide a device which is simple in construction, durable and efficient in operation and not 25 likely to get out of working order.

Reference is to be had to the accompanying drawings forming a part of this specification, in which similar characters of reference indicate corresponding parts in all 30 the views, and in which—

Figure 1 is an inside elevation of my improved elevator well door operator and lock illustrating its application, the door being shown closed in solid lines and open in 35 dotted lines; Fig. 2 is an enlarged sectional view vertically through the door and working parts of the device; Fig. 3 is a horizontal sectional view on the line 3—3 of Fig. 2; and Fig. 4 is a detail vertical sectional view 40 on the line 4—4 of Fig. 2.

In illustrating the application of my improved device, an elevator well door 10 is shown having rollers 11 slidably supporting the door on a runner or track 12 which 45 is suitably supported as within an elevator well 13 of the usual or any preferred construction but which in the present instance is shown as a frame-like structure. The numeral 14 designates the floor with which 50 the bottom of the door contacts, there being a suitable guide 15 in which the lower edge of the door operates when opened. While the device is shown as applied to an elevator well door or gate it is here explained that 55 it may be applied to other doors and that

the construction of the latter may vary in many respects without departing from the spirit of the invention. In the illustration the door 10 is shown constructed of a channel iron frame with the flanges 16 projecting inwardly and the intermediate or central portion of the door closed by a frame-like or foraminous structure.

Normally usually the well doors are provided with locking means positioned at the free vertical edge of the door co-operating with the well or frame forming the same, but in my present invention the locking means is provided at the opposite vertical edge and is operated at the free edge in the usual manner. For this purpose a bolt or bar 17 which is substantially horizontally disposed within the well at one side of the door opening with which the door 10 co-operates, is pivoted as shown at 18 so as to 75 swing vertically and has a reduced portion 19 at its free end formed by recessing its under edge or otherwise to provide a vertical shoulder 20 beneath the reduced portion. Secured to the inner side of the door 80 10 is a casting 21, the same having reduced apertured end portions bolted to the frame of the door which is channel shaped in cross section as heretofore described. The casting 21 is preferably located midway of the height of the door and is provided with a slot 22 therethrough while alined slots 23 are provided in the flanges of the door frame adjacent thereto, said slots being adapted to receive the reduced 85 extremity of the bolt or bar in the manner shown in Fig. 1 of the drawings so that the shoulder 20 will engage the edge portions 24 of the casting and thus hold the door locked in a closed position.

Pivoted intermediate its ends between the flanges of the other side of the door, as shown at 25, is an operating handle or lever 26 which at its lower end is pivotally connected as shown at 27 to a strap or link 28 100 having its inner end angularly bent or extended inwardly, as shown at 29, and apertured. The casting 22 beneath the slotted portion is provided with a recess 30 in which portion is provided with a recess 30 in 105 which a horizontally disposed trigger 31 is pivoted, as shown at 32, for vertical swinging movement, said trigger having a vertical extension or contacting portion 33 at its free end with a rounded 110

upper edge. An upright 34 is fixed rigid to the trigger 31 preferably intermediate its ends and extends upwardly above the bar or bolt 17 where it is pivotally connected, as shown at 35, by means of a rod 36 to the link 28. The end of the rod 36 which passes through the apertured bent portion of the link is threaded and has a nut 37 engaged thereon whereby when the rod is passed therethrough its length may be adjusted by means of the nut and the rod subsequently engaged in the upright, or vice versa, to regulate the length of the rod and consequently the throw or movement of the trigger 31.

The connection of the rod with the upright is rendered detachable so as to facilitate the connection and adjustment, and the innermost flange of the side of the frame carrying the member 26 is slotted, as shown at 38, to slidably receive the link 28 therethrough, so that when the parts are in the position shown in dotted lines in Fig. 1 of the drawings the lever will be vertically disposed and the trigger horizontally disposed so as to permit the bolt 17 to drop by its weight whereby the shoulder will contact with the casting and hold the door positively in a closed position. A spring 39 or other suitable means may be provided to hold the trigger downwardly to permit the bolt to drop, and in the present instance the spring is shown as attached to the trigger and to the frame of the door, thus positively insuring of the locking of the door upon the same being closed.

When it is desired to open the door the operator grasps the handle portion of the lever 26 and swings the same to the left on its pivot, thus drawing the rod 36 to the right and raising the trigger 31 on its pivot to contact with the bolt 17 so as to elevate the latter and disengage the shoulder from the casting. Continued pressure upon the lever will cause the door to be slid in its bearings and opened, when the rod will slide through the slots 23 and the door, through the medium of the slots, will slide over the bolt which will be accommodated in the slots together with and beneath the rod, the parts then taking the position shown in dotted lines in Fig. 1 of the drawings. In closing the door the operator swings the lever to the right, exerting a closing movement the same as in closing any sliding door, when the trigger 31 will be lowered on its pivot assisted by the spring 39, and disengaged from the bolt, while the door is moving to a closed position over the bolt which will again automatically drop to cause the shoulder 20 to engage the casting and hold the door positively in a closed position.

As a means to prevent operation of the device from the exterior of the well or door, especially when the same is constructed of

framework as distinguished from solid walls, a casing is provided between the vertical portions of the door to inclose the rod 36, said casing preferably embodying a front plate 40 and a back plate 41 having off-set top and bottom edges secured to the front plate and inclosing the rod therein.

Having thus described my invention, what I claim as new and desire to secure by Letters Patent is:—

1. The combination with a door supported for horizontal sliding movement and a bolt pivotally supported for vertical swinging movement and projecting toward the inner edge of the door; of a slotted support carried by the door frame, said bolt having a shoulder to engage the support with the reduced portion passing through the slot, said frame having slots in alinement with the slot of the support, a lever pivoted in the opposite side of the frame, a trigger pivoted in the support beneath the bolt and having an upwardly extending engaging portion to contact with the bolt, an upright fixed to the trigger, a frame adjacent to the lever having a slot therein, an adjustable connection between the upright and the lower end of the lever whereby when the lever is moved in the opening direction of the door the trigger will release the bolt and open the door whereby the door will slide over the bolt with the adjustable connection passing through the slots, movement of the lever in the opposite direction lowering the trigger to permit closing of the door, a spring normally lowering the trigger to permit the bolt to drop to engaged position for locking the door in closed position, and a casing across the door over the adjustable connection between the upright and lever to prevent operation thereof from the exterior.

2. The combination with an elevator well having a doorway and a gate slidable over the same; of locking means coöperating with the inner vertical edge of the door, an operating device carried by the door near its opposite vertical edge, means at the inner edge of the door independent of the locking means and connected to the operating member for releasing the locking device upon pressure being exerted there-against in the act of opening the door, said operating device when moved in the opposite direction also releasing the locking mechanism and permitting the door to be closed, and means normally holding said releasing mechanism inoperative to permit the locking mechanism to operate.

3. The combination with a door slidably supported having a slotted portion; of a pivoted bolt coöperating with said slotted portion to hold the door in a closed position, a trigger beneath said bolt, and a lever carried by the opposite portion of the door with respect to the slotted portion and op-

- eratively connected to the trigger for raising the latter to release the bolt and permit the door to be opened.
4. The combination with a door slidably supported having a slotted portion; of a pivoted bolt cooperating with said slotted portion to hold the door in a closed position, a trigger beneath said bolt, a lever carried by the opposite portion of the door with respect to the slotted portion and operatively connected to the trigger for shifting the latter to release the bolt and permit the door to be opened, said connection between the lever and the trigger being adjustable to vary the movement of the trigger, and means normally holding the lever in a neutral position and permitting the bolt to engage the door.
5. The combination with a door having a frame of channel metal, said door being supported for horizontal sliding movement, and a bolt pivotally supported for vertical swinging movement and projecting toward the inner edge of the door; of a slotted casting carried by the door frame, said bolt having a reduced portion forming a shoulder to engage the casting with the reduced portion passing through the slot, said frame having slots in alinement with the slot of the casting, a lever pivoted in the opposite side of the frame, a trigger pivoted in the casting beneath the bolt and having an upwardly extending engaging portion to contact with the bolt, an upright fixed to the trigger, a frame adjacent to the lever having a slot therein, and adjustable connection between the upright and the lower end of the lever whereby when the lever is moved in the opening direction of the door the trigger is raised to release the bolt and open the door whereby the door will slide over the bolt with the adjustable connection passing through the slots.
6. The combination with a door having a frame of channel metal, said door being supported for horizontal sliding movement, and a bolt pivotally supported for vertical swinging movement and projecting toward the inner edge of the door; of a slotted casting carried by the door frame, said bolt having a reduced portion forming a shoulder to engage the casting with the reduced portion passing through the slot, said frame having slots in alinement with the slot of the casting, a lever pivoted in the opposite side of the frame, a trigger pivoted in the casting beneath the bolt and having an upwardly extending engaging portion to contact with the bolt, an upright fixed to the trigger, a frame adjacent to the lever having a slot therein, and adjustable connection between the upright and the lower end of the lever whereby when the lever is moved in the opening direction of the door the trigger is raised to release the bolt and open the door whereby the door will slide over the bolt with the adjustable connection passing through the slots.

In testimony whereof I have signed my name to this specification in the presence of two subscribing witnesses.
